No. 831,182.

PATENTED SEPT. 18, 1906.

W. D. PALMER.
PRINTER'S BORDER.
APPLICATION FILED JAN. 31, 1906.

UNITED STATES PATENT OFFICE.

WARREN DWIGHT PALMER, OF NEW YORK, N. Y

PRINTER'S BORDER.

No. 831,182.

Specification of Letters Patent.

Patented Sept. 18, 1906.

Application filed January 31, 1906. Serial No. 298,760.

To all whom it may concern:

Be it known that I, WARREN DWIGHT PALMER, a citizen of the United States, residing in the borough of Brooklyn, in the city and county of New York, State of New York, have invented a certain new and useful Improvement Relating to Printers' Borders, of which the following is a specification.

The invention provides for holding completely continuous encircling rules.

I will describe particularly rectangular and circular forms; but there may be other forms, as elliptical or star shaped or various irregular shapes. There is always a difficulty in making perfect joints in such bordering and properly holding and releasing the rules and types or other printing devices inclosed.

I have discovered that a continuous border may be made of brass or other suitable material of the thickness of a double or single rule or of any other ordinary thickness with any desired form of face in one piece having the angles, if there are any, made absolutely continuous and to have the printing devices in side locked and unlocked by the ordinary means. My invention is based thereon. The same quoins and furniture and the same provisions for tightening thereby which confine and release the types outside may serve also by my invention to confine and release the types inside.

The following is a description of what I consider the best means of carrying out the invention.

The accompanying drawings form a part of this specification.

Figure 1 is a vertical section. Fig. 2 is a side view of a member which I term an "anchor," and Fig. 3 is an edge view of an ordinary space. Fig. 4 is a plan view of the entire form on a smaller scale. Fig. 5 is an end view of a portion corresponding to Fig. 4. Fig. 6 is a horizontal section on the line 6 6 in Fig. 5. Fig. 7 is a corresponding section of the slide ready to be inserted. Fig. 8 is a perspective of the rectangular border standing alone. The next three figures are outlines indicating successive stages in the operation of inserting the slide. Fig. 9 shows the slide with the long rabbet engaged, but standing obliquely. Fig. 10 shows the same after the slide has been moved endwise also pressed against the inclosed matter. Fig. 11 shows the same after it has been moved endwise to complete the engagement. The remaining figures show modifications. Fig. 12

is an end view corresponding to Fig. 5. Fig. 13 is a plan view of the furniture exterior to the rectangular border. Fig. 14 is a slide for the long side, showing two windows.

60

Similar letters and marks of reference indicate like parts in all the figures where they appear.

A is the bed of a press, and B represents printing devices, as types or cuts, or both, 65 properly arranged to produce the required effect in the printing.

C represents quadrats, often termed "quads," specially provided for this work, having less than the ordinary height, only 70 sufficient to afford reliable support for the inclosed types and to receive and transmit external pressure from the inclosing compressing devices in "locking up."

D is a continuous rule shown as circular. 75 It is of just sufficient height to rest on the upper ends of the quads and make the printing-surface on the upper edge of this ring exactly type-high. The ring D is formed with a number of windows (horizontal apertures 80 d) at about the mid-height.

E represents what I will term "anchors," thin pieces of brass or other suitable material little less than space-high, each presenting a horizontal locking-arm E' at its upper end. 85

M is an ordinary chase, N ordinary furniture, and O ordinary quoins.

In composing the matter care is taken to so arrange any printing devices which are to appear outside of the circular ring D that 90 there remains a clear space having more width than the ring, so that the latter may be applied at a later stage and the locking and unlocking may allow the supporting-quads and the engaging anchors to move a little in 95 the acts of locking and unlocking the forms.

The horizontal arms or ridges E' on the several anchors need not be long. They must be sufficiently shallow to each enter a window d and press downward with gentle 100 force by its lower edge on the lower edge of the window.

It is essential that the ring D shall be held down to its bearing on the quads below without any rattling and also that the friction 105 shall not be so great as to prevent the quads C and the anchors E E' from moving radially toward and from the center of the ring D to allow all the motion ever required in ordinary locking and unlocking.

The quads C and the printing matter F in the cases where printing is also to be effected

110

outside of the ring D are so arranged as to make a "form" of an ordinary rectangular outline inclosed in an ordinary rectangular chase M and compressed from outside by 5 furniture N and by quoins O.

G G are the long sides, and H H the short ones, of a body forming a continuous rule extending quite around, so as to present and print a complete oblong rectangle. Each of 10 the ends H has a liberal aperture h, extending a large portion of the distance across the end, which aperture I will term a "window." Each long side G has a corresponding window. I have shown two. There may be 15 two or a greater number of such windows in each of the sides. They perform an important function in allowing a horizontal pressure applied from without to be felt by the types, quads, or other printing matter within. 20 The inner face of each short side H is excavated adjacent to each end of each window h, forming pockets h' and h''.

I is a separately-formed piece, which I will term a "slide," because the sliding is an important function. Its width is a little less than that of the window h. Its ends are reduced in thickness on the outer side, as indicated by the rabbets i' and i'', the reduction i'' being the longest. This piece may be introduced and held in position temporarily before the rectangle G H is placed in position; but I give the preference to applying the rectangle, which I will term this "four-sided form" of the continuous rule, first, and 30 applying the slide I afterward. The movements for thus applying the slide after the interior matter is in place are first to insert the end having the long rabbet i'' in the window as nearly as practicable in line with the part 35 G and sliding it endwise until the rabbeted part i'' is received in the proper pocket h''. When this movement has been carried to the proper extent, the other end of the slide I, having the short rabbet i', will be in such position that the slide may by a pressure of the 40 finger or of any suitable instrument be pressed inward, slightly compressing the printing material inside and bringing the slide into such position that its short rabbet 45 i' can catch. Now an endwise sliding movement of the slide in the opposite direction to the first draws the long rabbet partly out of its engagement and engages the short rabbet i' with the pocket h', and the introduction of 50 this slide is completed.

If there are, as shown, two windows in a side, the slides I must be thinned also, each at its mid-length, to allow for the material of G which lies between its windows. The 55 "bridge," if such it may be called, between the adjacent windows g is thinned by removing some of the metal on the outer side, as will be understood, to allow for more motion in the locking.

65 Two corresponding slides J are provided,

adapted to engage in the corresponding pockets g' g''. Each has a short rabbet j' and a long rabbet j''. The inner faces of the end H are correspondingly pocketed by thinning at the points h' and h'', and the slides J are introduced in the same manner as the slides I, already described.

It will be understood that the slides should be thicker than the body G and H; but I will suggest means below for remedying the difficulty if there is too little thickness of the slides. The outer face of each slide should be ridged vertically or otherwise roughed to provide a good "hold" for giving the endwise movements. The whole quantity of 80 type, &c., within the rectangle G H should be judiciously determined, so that as the locking is effected by tightening the quoins in any ordinary or suitable manner when the compression of the inclosed matter by the inward movement of the slides I and J will be arrested by having taken up all the slack on the matter inclosed within the rectangle the pressure of the furniture on the general exterior of the parts G and H will have taken up 85 all the slack outside thereof, so that all will be held firmly.

N N are pieces of "furniture" of the ordinary height pressed inward and released at will by ordinary means in use, being pressed 90 inward to effect the locking of the form and relaxed and allowed to move outward with or without assistance from the operator when it becomes desirable to unlock the form to remove the type or make any changes therein. In being pressed inward the furniture presses with its inner face against the outer face of slide I or J, which lies within it. In 95 doing so it forces the slide inward toward the center of the form and imparts to the devices B the same pressure which obtains outside. When the furniture is pressed inward, the 100 form not only outside but inside of the ring D is locked.

Modifications may be made without departing from the principle or sacrificing the 110 advantages of the invention.

Parts of the invention may be used without the whole. I can use the ring D and the provisions for holding it by the aid of its windows d without the rectangle, or I can use the rectangle G H and the provisions for holding the whole of the matter interior thereto by the aid of its windows g and h on two or more sides without the ring. I prefer the whole 115 used together, as shown.

There may be only one side and one end window provided with slides, making the other side and the other end solid. Such arrangement may be preferable in most cases. The recesses or pockets to receive the ends of the slides may be omitted, the types within 120 requiring to be more compressed by the force applied in inserting the slide. When the recesses are provided, both may be long.

The metal below each window may be reduced or such metal may be omitted entirely. The metal at the top or printing-face can by such modification be made deeper 5 and better able to bear the force received in the acts of printing. Such modification is shown in Fig. 12. It may be expedient where the parts G and H are of type-metal or other weak material.

10 In most cases where the slides are not sufficiently thick the inner faces of the furniture may be thicker by pasteboard or leads applied in the positions opposite the window. Fig. 13 shows such a modification, N' being 15 the thin material pasted or nailed on the furniture N.

I claim as my invention—

1. A printer's border having an upper edge or effective portion extended continuously to 20 form a complete circuit, provided with apertures near the mid-height in combination with a chase and provisions for locking the material within such border by applying force from outside, the connection being ef-

fected by slides I having rabbeted ends adapted to be introduced from outside and to be engaged and liberated by endwise movements, all substantially as herein specified. 25

2. A printer's border having an upper edge or effective portion extended continuously to 30 form a complete circuit, provided with apertures near the mid-height in combination with a chase and provisions for locking the material within such border by applying force from outside, the connection being ef- 35 fected by anchors E, adapted to be inserted between the bodies of shallow parts as low quads C, outside, and having each an arm E' arranged to extend inward through an aperture and hold the rule down, all substantially 40 as herein specified.

Signed at New York city, in the county and State of New York, this 27th day of January, A. D. 1906.

WARREN DWIGHT PALMER.
